UNITED STATES PATENT OFFICE.

JAMES P. MOSIER, OF ST. FRANCOIS, MISSOURI, ASSIGNOR, BY MESNE ASSIGNMENTS, OF ONE-FOURTH TO HIMSELF, ONE-EIGHTH TO ERNIST R. CAMPBELL, AND ONE-EIGHTH TO JOHN A. GREEN, BOTH OF DESLOGE, MISSOURI, AND ONE-HALF TO NATIONAL LEAD COMPANY, OF ST. LOUIS, MISSOURI, A CORPORATION OF NEW JERSEY.

ROTARY CAR DUMP.

1,424,510.

Specification of Letters Patent. Patented Aug. 1, 1922.

Application filed August 19, 1920. Serial No. 404,636.

To all whom it may concern:

Be it known that I, JAMES P. MOSIER, a citizen of the United States, and a resident of the city of St. Francois, in the county of St. Francois and State of Missouri, have invented a new and useful Improvement in Rotary Car Dumps, of which the following is a specification.

My invention relates to means for dumping ore cars and the like and has for its principal objects to expedite and cheapen the operation of dumping such cars. The invention consists partly in providing a resilient support for one side of a rotatable dumping frame and in providing means for forcing said frame against said resilient support to initiate rotation of the frame. The invention also consists in locating the axis of rotation of said frame between said support and the center of gravity of the frame with a string of loaded cars thereon. The invention further consists in means for improving the purchase of the hoisting means on said frame. The invention further consists in the parts and combinations of parts hereinafter described and claimed.

In the drawings which form part of this specification and wherein like reference characters indicate like parts wherever they occur.

Fig. 1 is an elevation of a dumping mechanism embodying my invention, a portion thereof being a section taken on the line 1—1 of Fig. 2;

Fig. 2 is a side elevation thereof;

Fig. 3 is an end view, partly in section, showing the device after the frame has been rotated; and

Fig. 4 is a fragmentary side elevation showing the device after the frame has been rotated.

My device comprises a rotatable frame having rails 2 mounted thereon to form a trackway. The frame is arranged over a dumping pit and its trackway is arranged to be normally in alinement with and form a separate section of a main trackway on which run cars 30.

The frame is provided at each end with a

longitudinally projecting trunnion 3 so as to 50 be rotatable about a longitudinal axis. The axis is located so as to be offset from the center of gravity of the dump with a string of loaded cars thereon. Preferably, the trunnions 3 are offset from the median plane of 55 the frame, as indicated by dot and dash lines in Fig. 1. The frame comprises suitable longitudinal members 4 and cross pieces 5. Supports 6 are secured to the frame at intervals and support an angle iron 7 or like 60 guard hanger above each rail of the track, said angle irons 7 preferably being disposed with a flange 8 projecting horizontally over the track and located above the track a distance slightly greater than the diameter of 65 a car wheel 31. Said guard hangers may be located so as to engage the tops of the cars or projections on the sides of the cars; or separate grappling members may be provided for each car. An upright 9 comprising an I-beam or the like is secured to the frame near the middle thereof. A heavy coil spring 10 is mounted on a support 11 adjacent to the lower end of said upright. A bracket 12 projects outwardly from the lower end portion of said upright 9 and extends over said spring 10. A curved channel iron 13 or the like is secured to said upright and said bracket. A cable 14 or chain is secured to the upright 9 near the top thereof and one 80 end of said cable is connected by suitable rigging 15 to the end of the cable of any suitable winding mechanism 16. By means of said cable 14 and upright said bracket is normally held against said spring, thus supporting the frame in position with its trackway in alinement with the main trackway.

The normal position of the device is shown in Fig. 1, the frame being held with its trackway in alinement with the main trackway 90 and the cable 14 being held taut. As above indicated, there is a tendency for the frame to rotate because of the location of the longitudinal axis with reference to the center of gravity. To dump the cars, the cable is 95 pulled by means of the winding mechanism and the bracket 12 is thus forced against the spring 10. The pull is quickly released and

the reaction of the spring initiates a rotation of the frame. When the frame reaches the dumping position, the rotation is checked by means of the cable. The frame is rotated to 5 normal position by means of the winding mechanism and cable. The bracket holds the cable away from the upright, when the frame is in dumping position and increases the purchase of the winding mechanism on 10 the upright. The curved channel iron 13 serves as a guideway for the cable.

My device is especially useful in mines. The cars are held on the dumping frame without the necessity of fastening each car 15 separately. The cars are easily and quickly dumped, and comparatively little power is required in dumping and raising the frame by reason of the facts that the axis of rotation is offset and the cable is held away from 20 the upright.

An automatic stop may be arranged on the rails of the main trackway to prevent cars from running on to the frame while it is being dumped. It is obvious that numerous 25 changes may be made without departing from my invention and I do not wish to be limited to the precise construction shown.

What I claim is:

1. A car dump comprising a trackway, a 30 frame pivotally mounted to rotate on an axis substantially parallel with the trackway and having a separate section of trackway mounted thereon, guard hangers on said frame in position to overlap the wheels of 35 a car thereon, and means for normally holding said frame with its trackway section in operative relation to the main trackway, said means comprising a resilient member in the path of one side of the frame adapted 40 to aid in initiating the dumping movement thereof and in checking the movement to normal position.

2. A car dump comprising a trackway, a frame pivotally mounted to rotate on an axis 45 substantially parallel with the trackway and having a separate section of trackway mounted thereon, guard hangers on said frame in position to overlap the wheels of a car thereon, and means for normally holding 50 said frame with its trackway section in operative relation to the main trackway, said means comprising a resilient support for one side of said frame, and means for pulling said frame downwardly against said 55 resilient support and for releasing the pull to permit the resilient member to initiate a rotation of said frame.

3. A car dump comprising a trackway, a frame pivotally mounted to rotate on an 60 axis substantially parallel with the trackway and having a separate section of trackway mounted thereon, said axis being offset from a vertical plane passing through the middle of said trackway, means on said 65 frame for holding cars thereon, and means

for normally holding said frame with its trackway section in operative relation to the main trackway, said means comprising a resilient member in the path of one side of the frame adapted to aid in initiating the 70 dumping movement thereof and in checking the movement to normal position.

4. A car dump comprising a trackway, a frame pivotally mounted to rotate on an axis substantially parallel with the trackway 75 and having a separate section of trackway mounted thereon, said axis being offset from a vertical plane passing through the middle of said trackway, means on said frame for holding cars thereon, and means 80 for normally holding said frame with its trackway section in operative relation to the main trackway, said means comprising a resilient support for one side of said frame, and means for pulling said frame 85 downwardly against said resilient support to permit said resilient member to initiate a rotation of said frame.

5. A car dump comprising a frame pivotally mounted on a longitudinally extending axis, a trackway thereon adapted to accommodate the car wheels, guard hangers mounted on said frame far enough above the track to clear the car wheels slightly, an upright fixed at one side of said frame, 90 a support for said side of the frame comprising a vertically acting spring and means for pulling transversely of the trackway on the upper end of said upright, said longitudinal axis being located so as to be between said upright and the center of gravity of said car dump with a string of loaded cars thereon and said pulling means being quickly releasable to enable the reaction of the spring to initiate the rotation of said 100 frame.

6. A car dump comprising a frame pivotally mounted on a longitudinally extending axis, a trackway thereon adapted to accommodate the car wheels, guard hangers mounted on said frame far enough above the track to clear the car wheels slightly, an upright fixed at one side of said frame, 110 a support for said side of the frame comprising a vertically acting spring and quickly releasable means for pulling transversely of the trackway on the upper end of said upright, said longitudinal axis being located between said upright and the center of gravity of the car dump whereby 115 the quick release of said pulling means enables the reaction of the spring to initiate the rotation of said frame.

7. A car dump comprising a frame pivotally mounted on a longitudinally extending 125 axis, said axis being offset sidewise from the center of gravity of the car dump, a trackway on said frame adapted to accommodate the car wheels, guard hangers mounted on said frame far enough above 130

the track to clear the car wheels slightly, an upright fixed at the lighter side of said frame, a support for said side of the frame comprising a vertically acting spring, a cable secured to the upper end of said upright and to a winding mechanism and a bracket secured to said upright, said bracket

holding said cable away from said upright when the frame has been rotated, whereby leverage is obtained for raising said frame to normal position.

Signed at St. Louis, Missouri, this 16th day of August, 1920.

JAMES P. MOSIER.
